UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

FASTENER-INSERTING MACHINE.

1,245,887.

Specification of Letters Patent.

Patented Nov. 6, 1917.

Application filed July 26, 1915. Serial No. 41,874.

To all whom it may concern:

Be it known that I, STEPHEN A. DOBYNE, a citizen of the United States, and residing at St. Louis, in the State of Missouri, have 5 invented a certain new and useful Improvement in Fastener-Inserting Machines, of which the following is a specification.

This invention relates to fastener inserting machines, and more particularly, to machines for attaching soles to shoes.

In the operation of attaching soles to shoes, and more particularly in the operation of attaching the welt by a metallic fastener passing through the upper and insole, 15 it is desirable that the welt have a uniform or controlled projection. Now around the toe the upper projects or curves more away from the insole edge than at the sides. Furthermore where a toe cap is used this curve 20 or projection is enhanced by the stiff cap and by the additional thickness of the cap. Where the fastener seam is gaged by the contour of the insole, the gage must be shifted away from the horn when going 25 around the toe in order to compensate for this additional projection of the upper. Furthermore it is desirable that the length of the fastener be increased when going around the toe in order to securely fasten 30 the stiff and heavy toe cap.

One of the objects of this invention, therefore, is to provide a fastener inserting machine in which the gage is adapted to be shifted to one position when passing around 35 the toe and to another position when passing along the sides, so as to compensate for the projection at the toe and form a uniform seam.

Another object is to provide a fastener inserting machine in which both the gage and the fastener supplying mechanism are capable of control so as to vary the position of the seam, and so as to also vary the length of the fasteners, during the operation of the 45 machine.

Further objects will appear from the detail description taken in connection with the accompanying drawing, in which:

Figure 1 is a front elevation of a machine embodying this invention;

Fig. 2 is a side elevation;

Fig. 3 is a section on the line 3—3, Fig. 2;

Fig. 4 is a detail perspective view, and Figs. 5 and 6 are details showing the op-

eration along the sides and around the toe 55 respectively.

The general type of machine to which this invention is shown as applied is shown in United States Patent Number 1,091,298, March 24, 1914, and is more particularly 60 illustrated in my co-pending application, Serial Number 830,050, filed April 6, 1914. In the drawings hereinafter to be referred to, similar parts are designated by the same reference characters as in said application. 65

Referring, now, to the accompanying drawings, and more particularly in a general way to those parts fully illustrated and described in the application referred to, 10 designates a column or pillar which has 70 mounted thereon a machine head 11, provided with a driving shaft 12, which driving shaft has mounted thereon a series of cams for operating different parts of the machine. The machine is also provided with 75 a horn 23, adapted to receive and support the shoe. An awl bar 42 carries an awl 55, which forms fastener receiving openings and also feeds the work. A driver bar 61 carries a driver 60, which operates in a laterally movable throat 72 to drive the fasteners. A fastener stock guide 97 is provided with grooves 98 for the fastener stock, which is in the form of strings of connected 80 nails, and an arm 129 carrying a cutter 133 85 operates to sever the fasteners from the fastener stock preparatory to operation of the driver to drive the same into the work.

The member 95, which carries the guide 97, is rigidly mounted on the end of a shaft 90 96, which passes through a hollow sleeve or shank 70 on the throat, so as to oscillate concentrically with the throat. A spring stop plate 99 is mounted on an arm 100 of the member 95, and this plate bears against 95 the guide 97 to form a stop for the nail strings. A pin 102 is mounted on a projecting arm on the member 95, and engages one end of a spring 103, the other end of which is attached at 104 to the machine 100 head.

The shaft 96 is reduced in diameter at 105, and has rigidly mounted thereon a spool or collar 106 engaged by the forked end 107 of a shift lever 108 which is pivoted at 109 on a bracket 110 having gears 111, whereby it may be secured to the machine head by screws 112. A wedge shaped

2
spring pressed slide block or plunger 114 is mounted in a bore in the bracket 110, so as to engage a wedge shaped block 115 secured to the under side of the lever 108. This 5 wedge shaped block 115 is adapted to be moved into engagement with either one of the screw stops 116 adjustably mounted in an upwardly extending spaced lugs 117 on an extension 118 of the bracket 110. The screw 10 stops 116 are provided with lock nuts to lock them in adjusted positions. A spring 120 bears, at one end, against the spool 106, and, at the other end, against the machine head. The parts so far described are fully 15 shown and described in the above mentioned application.

A bracket *a* is mounted on the column 10, and is provided with a guide receiving a gage *b* which is adapted to bear against the 20 upper opposite the insole, of the shoe *X* mounted on the horn 23. The gage thus forms a sole edge gage. The gage is provided with a rack *d* which meshes with a pinion on a shaft *e* mounted in the bracket 25 *a*, and this shaft has a downwardly projecting handle *f* whereby the gage may be adjusted. An upwardly extending arm *g* on the shaft *e* has connected thereto a link *h* whose threaded end extends through a sleeve 30 *i* swiveled on the arm 108, and having nuts *j* adapted to bear against the sleeve; the strings of connected nails are indicated at 35 *k* and *l*, the strings having nails of different sizes. The welt *c* is guided under the presser foot 20 by a welt guide *x* fixed to the machine head, and, therefore, fixed with respect to the driver.

The fastener stock guide 97 can be shifted 40 forwardly and backwardly to position either one of the fastener stock receiving grooves 98 in alinement with the driver passage and the cutter 133. Thus, in the position of parts as shown in the drawings, the left hand 45 groove, Fig. 2, carrying the smaller nails, is positioned in alinement with the driver passage and the cutter. The gage *b* is, at this time, in its forward position, nearest the driver passage. The lever 108 is also, at this time, in position, with the wedge shaped 50 block 115 in engagement with the forward stop, Fig. 3. The parts will be held in this position by means of the wedge shaped block 115, and the gage is also, of course, frictionally held in the bracket *a* in the usual manner, by providing the shaft *e* with a collar *m* and with nuts *n*, so as to clamp this shaft 55 frictionally in the bracket *a*. The parts will thus be held in the position of adjustment. Both the fastener stock guide and the gage 60 can be shifted either by the operation of the lever 108 or of the arm *f*, so as to shift the other nail string, having the longer nails, into alinement with the driver passage, and so as to shift the gage back away from the 65 driver passage. As the parts are moved the

block 114 will yield and will then snap on the other side of the block 115, so as to again secure the parts in adjusted position. Either of the grooves 98 may be alined with respect to the driver passage by the adjustment of the proper stop 116, and this adjustment may be independent for each groove. Moreover, by the adjustment of the nuts *j*, the gage can be independently adjusted so as to occupy any desired position, and by adjusting these nuts so as to provide for a lost motion between the gage and the fastener stock guide, the gage may be moved any desired distance from zero to a maximum during the shift from one size 70 fastener to the other, it being understood that this gage is held in position on account of its frictional engagement with the bracket. By placing the spring 120 between the guide shaft and the machine head the end play of 75 the parts is kept constant and on one side and in one direction. The shoe having been placed on the horn, and the welt in the welt guide, the operator proceeds to nail around the shoe. While nailing along the sides, the 80 gage lies close to the driver passage, as shown in Fig. 5, and the fastener stock guide stands in position to hold the nail string *k* having the shorter nails in alinement with the throat and cutter, as shown in the drawings. When nailing around the toe, the gage is thrown out away from the driver passage 85 so as to compensate for the projection at the toe cap, and simultaneously the fastener stock guide is shifted so as to place the nail string *l* having the longer nails in alinement with the throat and the cutter. It is, therefore, insured that the welt will have a uniform projection with respect to the guiding base, namely the edge of the insole, and the 90 seam will also be placed at a uniform position with respect to this base and the cutter. The capability of independent adjustment of the gage and the fastener stock guide enables the machine to accommodate itself to all 95 classes of work. Thus it is sometimes desirable that the projection of the welt on the 100 sides vary, as for different extension edges.

In such a case, however, it is not desirable 105 to change the length of the fasteners. In accordance with this invention, this can be accomplished by the separate adjustment between the gage and the nail guide, and more especially through the capability for lost motion. By providing a certain lost 110 motion between the nuts *j* on link *h* and the sleeve *i*, the gage itself may be shifted through certain limits before the lever 108 will be actuated to shift the nail guide. The operator can thus when operating along the 115 sides shift the gage to provide, for instance, for a different extension along the fore-part than along the shank, or a still different extension along the ball than along the inside 120 edge, the parts working at this time on the 125 edge, the parts working at this time on the 130

lost motion connection. When the toe cap is reached the gage can be shifted still farther to shift the nail guide to feed the longer nail. The guide and gage may, of course, be shifted during the operation of the machine, which, of course, is necessary when nailing around a shoe.

While the invention has been illustrated in connection with a welt attaching machine, it is obvious that it may be applied to a machine in which the outsole is directly attached to the lasted upper, the welt guide being in such a case removed.

It is further obvious that various changes may be made in the details of construction without departing from the spirit of this invention. It is, therefore, to be understood that this invention is not to be limited to the specific construction shown and described.

Having thus described the invention what is claimed is:

1. A machine for fastening soles to shoes, comprising a shoe horn adapted to enter and support a McKay-lasted upper, a shiftable sole edge gage constructed and arranged to bear against the upper opposite the insole, fastener inserting mechanism, mechanism for supplying fasteners of different kinds to said fastener inserting mechanism, and means for shifting said sole edge gage and said fastener supplying mechanism.

2. A machine for fastening soles to shoes, comprising a shoe horn adapted to enter and support a McKay-lasted upper, a shiftable sole edge gage constructed and arranged to bear against the upper opposite the insole, fastener inserting mechanism, mechanism for supplying fasteners of different kinds to said fastener inserting mechanism, and means operated upon adjustment of said sole edge gage for causing said fastener supplying mechanism to stop supplying fasteners of one kind and supply fasteners of another kind.

3. A machine for fastening soles to shoes, comprising a shoe horn adapted to enter and support a MacKay-lasted upper, a shiftable sole edge gage constructed and arranged to bear against the upper opposite the insole, fastener inserting mechanism, mechanism for supplying fasteners of different kinds to said fastener inserting mechanism, means for shifting said sole edge gage and said fastener supplying mechanism, and means for independently adjusting said gage relative to said shifting means.

4. A machine for fastening soles to shoes, comprising a shoe horn adapted to enter and support a McKay-lasted upper, a shiftable sole edge gage constructed and arranged to bear against the upper opposite the insole, fastener inserting mechanism, mechanism for supplying fasteners of different kinds to said fastener inserting mechanism, means operated upon adjustment of said sole edge

gage for causing said fastener supplying mechanism to stop supplying fasteners of one kind and supply fasteners of another kind, and means for independently adjusting said sole edge gage relative to said shifting means.

5. A machine for fastening soles to shoes, comprising a shoe horn adapted to enter and support a McKay-lasted upper, a shiftable sole edge gage constructed and arranged to bear against the upper opposite the insole, fastener inserting mechanism, mechanism for supplying fasteners of different kinds to said fastener inserting mechanism, and a shifting member connected to shift said sole edge gage and said fastener supplying mechanism.

6. A machine for fastening soles to shoes, comprising a shoe horn adapted to enter and support a McKay-lasted upper, a shiftable sole edge gage constructed and arranged to bear against the upper opposite the insole, fastener inserting mechanism, mechanism for supplying fasteners of different kinds to said fastener inserting mechanism, a shifting member connected to shift said sole edge gage and said fastener supplying mechanism, and means for adjusting said gage with respect to said shifting member.

7. In a machine of the class described, a shoe horn adapted to enter and support a McKay-lasted upper, fastener inserting mechanism, a shiftable fastener stock guide for supplying a plurality of strands of fastener stock to said fastener inserting mechanism, a shiftable work gage constructed and arranged to bear against the upper opposite the insole, and a shifting member connected to shift said fastener stock guide and said work gage.

8. In a machine of the class described, a shoe horn adapted to enter and support a McKay-lasted upper, fastener inserting mechanism, a shiftable fastener stock guide for supplying a plurality of strands of fastener stock to said fastener inserting mechanism, a shiftable work gage constructed and arranged to bear against the upper opposite the insole, and a shifting member connected to shift said fastener stock guide and said work gage, constructed to retain the parts in shifted position.

9. In a machine of the class described, a shoe horn adapted to enter and support a McKay-lasted upper, fastener inserting mechanism, a shiftable fastener stock guide for supplying a plurality of strands of fastener stock to said fastener inserting mechanism, a shiftable work gage constructed and arranged to bear against the upper opposite the insole, a shifting member connected to shift said fastener stock guide and said work gage, and means for adjusting said work gage with respect to said shifting member.

10. In a machine of the class described, a shoe horn adapted to enter and support a McKay-lasted upper, fastener inserting mechanism, a shiftable fastener stock guide for supplying a plurality of strands of fastener stock to said fastener inserting mechanism, a cutter adapted to sever fasteners from the fastener stock, a shiftable work gage constructed and arranged to bear against the upper opposite the insole, and a shifting member connected to shift said fastener stock guide and said work gage. 5
11. In a string nailing machine, a shoe horn adapted to enter and support a McKay-lasted upper, a driver, a shiftable guide for a plurality of nail strings, a cutter for severing the nails from the strings, a shiftable work gage constructed and arranged to bear against the upper opposite the insole, and a shifting member connected to shift said fastener stock guide and said work gage. 10
12. In a string nailing machine, a shoe horn adapted to enter and support a McKay-lasted upper, a driver, a shiftable guide for a plurality of nail strings, a cutter for severing the nails from the strings, a shiftable work gage constructed and arranged to bear against the upper opposite the insole, a shifting member connected to shift said fastener stock guide and said work gage, and means for adjusting said gage with respect to said shifting member. 15
13. A machine for fastening soles to shoes, comprising a shoe horn adapted to enter and support a McKay-lasted upper, a sole edge gage constructed and arranged to bear against the upper opposite the insole, fastener inserting mechanism, means for shifting said sole edge gage away from the fastener inserting mechanism when passing around the toe, and means for adjusting the shifting movement of the gage adapted to compensate for the projection of the upper at the toe. 20
14. A machine for fastening soles to shoes, comprising a shoe horn adapted to enter and support a McKay-lasted upper, fastener inserting mechanism, a sole edge gage engaging the upper of the shoe opposite the insole to guide the shoe during the fastener inserting operation by the contour of the insole, means for shifting said sole edge gage away from the fastener inserting mechanism when passing around the toe, and means for adjusting the shifting movement of the gage adapted to compensate for the projection of the upper at the toe. 25
15. A machine for fastening soles to shoes, comprising a shoe horn adapted to enter and support a McKay-lasted upper, fastener inserting mechanism, a welt guide, a sole edge gage engaging the upper of the shoe opposite the insole to guide the shoe during the fastener inserting operation by the contour of the insole, means for shifting said sole edge gage away from the fastener inserting mechanism and the welt guide when passing around the toe, and means for adjusting the shifting movement of the gage adapted to compensate for the projection of the upper at the toe. 30
16. A machine for fastening soles to shoes, comprising a shoe horn adapted to enter and support a McKay-lasted upper, a sole edge gage, fastener inserting mechanism, mechanism for supplying fasteners of different kinds to said fastener inserting mechanism, and means for concurrently shifting said sole edge gage and said supplying mechanism when passing around the toe adapted to compensate for the projection of the upper at the toe, and vary the kind of the fastener driven at the toe. 35
17. A machine for fastening soles to shoes, comprising a shoe support, fastener inserting mechanism, a welt guide, a gage engaging the upper of the shoe opposite the insole to guide the shoe during the fastener inserting operation by the contour of the insole, mechanism for supplying different lengths of fasteners to said fastener inserting mechanism, and means for shifting said gage away from the fastener inserting mechanism and the welt guide when passing around the toe and for concurrently shifting said supplying mechanism, adapted to compensate for the projection of the upper at the toe and increase the length of nail driven at the toe. 40
18. A machine for fastening soles to shoes, comprising a shoe support, fastener inserting mechanism, a welt guide, a gage engaging the upper of the shoe opposite the insole to guide the shoe during the fastener inserting operation by the contour of the insole, mechanism for supplying different lengths of fasteners to said fastener inserting mechanism, means for shifting said gage away from the fastener inserting mechanism and the welt guide when passing around the toe and for concurrently shifting said supplying mechanism, adapted to compensate for the projection of the upper at the toe and increase the length of nail driven at the toe, and means for independently shifting said gage when passing along the sides of the shoe. 45
19. A machine for fastening soles to shoes, comprising a shoe horn adapted to enter and support a McKay-lasted upper, a welt guide, a sole edge gage, fastener inserting mechanism, mechanism for supplying fasteners of different kinds to said fastener inserting mechanism, and means for shifting said gage and said supplying mechanism. 50
20. A machine for fastening soles to shoes, comprising a shoe horn adapted to enter and support a McKay-lasted upper, a welt guide, a sole edge gage, fastener in- 55

serting mechanism, mechanism for supplying fasteners of different kinds to said fastener inserting mechanism, and a shifting member connected to shift said gage and 5 said supplying mechanism.

21. A machine for fastening soles to shoes, comprising a shoe horn adapted to enter and support a McKay-lasted upper, a sole edge gage, fastener inserting mechanism, mechanism for supplying fasteners of different kinds to said fastener inserting mechanism, a shifting member connected to shift said gage and said supplying means, and means adapting the gage for movement 10 by said shifting member independently of 15 said supplying mechanism.

22. A machine for fastening soles to shoes, comprising a shoe horn adapted to enter and support a McKay-lasted upper, a sole edge gage, fastener inserting mechanism, mechanism for supplying fasteners of different kinds to said fastener inserting mechanism, a shifting member connected to shift said gage and said supplying means, and means adapting said gage for movement 20 by said shifting member, within predetermined limits, independently of said supplying mechanism.

In testimony whereof I affix my signature this 1st. day of May, 1915.

STEPHEN A. DOBYNE.
